REAR VISION VISOR FOR A HELMET

Wyl Kenneth Crowder, 3255 Windcroft Drive,
Pontiac, Mich. 48054

Filed July 30, 1969, Ser. No. 18,473

Term of patent 14 years

Int. Cl. D2—03

U.S. Cl. D2—233

Fig. 1

Fig. 2

FIG. 1 is a side perspective view of a rear vision visor for a helmet showing my new design, the side opposite that shown being substantially a mirror image thereof; and

FIG. 2 is a rear elevational view thereof.

I claim:

The ornamental design for a rear vision visor for a helmet, substantially as shown and described.
